UNITED STATES PATENT OFFICE

109,867

DESIGN FOR SHOE UPPER MATERIAL

Charles H. Caldwell, Brockton, Mass., assignor to
Geo. E. Keith Company, Campello, Mass., a
corporation of Massachusetts

Application December 28, 1937, Serial No. 73,900

Term of patent 3½ years

To whom it may concern:

Be it known that I, Charles H. Caldwell, a citizen of the United States, residing at Brockton, in the county of Plymouth and State of Massachusetts, have invented a new, original, and ornamental Design for Shoe Upper Material, of which the following is a specification, reference being had to the accompanying drawing, forming part thereof.

In the drawing, the figure is a plan view of a piece of shoe upper material showing my new design.

The essential feature of the invention resides in

the arrangement of small and large perforations, the small being arranged in wavy lines, bordered by stitching; and the large being segmental in shape accenting the troughs and crests of the waves by being positioned in the troughs and over the crests of each wavy line in the clear wavy space between adjacent wavy stitched borders.

I claim:

The ornamental design for shoe upper material, as shown and described.

CHARLES H. CALDWELL.
